(57) **CLAIM**

We claim the ornamental design for a lug nut with sleeve, as shown and described.

DESCRIPTION

FIG. 1 is a perspective view of a lug nut with sleeve, showing our new design;

FIG. 2 is an exploded perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a cross-sectional view thereof, taken along line 9-9 of FIG. 7.

1 Claim, 5 Drawing Sheets
